UNITED STATES PATENT OFFICE.

CHARLEY W. BARKER AND VIRGIL T. FISH, OF VICTOR, IOWA.

SHOE POLISHER.

Application filed January 17, 1923. Serial No. 613,207.

To all whom it may concern:

Be it known that CHARLEY W. BARKER and VIRGIL T. FISH, citizens of the United States, residing at Victor, in the county of 5 Iowa and State of Iowa, have invented certain new and useful Improvements in Shoe Polishers, of which the following is a specification.

This invention relates to improvements in 10 shoe polishers and has as one of its primary objects to provide a polishing device which may be conveniently manipulated to impart a high polish to shoes of all kinds without any likelihood of marring of the leather 15 or any inconvenience to the user if troubled with corns or other foot ailments, the invention contemplating, in this connection, the provision of a polisher in which the polishing medium will be not only in itself 20 soft and pliable, but will, furthermore, be resiliently supported so as to adapt it to yield when brought in contact with the shoe being polished.

Another important object of the invention 25 is to provide a polisher which may be employed in polishing both black and tan shoes without likelihood of the polish employed upon one kind of shoe being applied to the other kind of shoe.

Another object of the invention is to so 30 construct the polisher that regardless of the manner in which it is held in polishing a shoe, a soft and more or less yieldable surface will be presented to the palm of the 35 hand so as not to inconvenience the user.

Another object of the invention is to provide 40 a polisher which may be economically manufactured and which will be durable and capable of being cleansed when occasion requires.

In the accompanying drawings:

Figure 1 is a perspective view of the polisher embodying the present invention;

Figure 2 is a vertical longitudinal sectional view through the polisher;

Figure 3 is a vertical transverse sectional view through the polisher taken substantially on the line 3—3 of Figure 2 locking in the direction indicated by the arrows.

The polisher embodying the invention 50 includes in its structure a body or core which is indicated by the numeral 1 and comprises a body portion 2 which is preferably in the form of a rectangular sheet of heavy and 55 relatively stiff leather such, for example, as

sole leather. The body or core 1 further comprises plies 3 of leather which are stapled or otherwise united, as at 4, at their ends to the opposite faces of the body 2 at the ends of said body. The plies 3 are preferably not quite so heavy or rigid as the body sheet 2 and are of somewhat greater length than the said body sheet so that their intermediate portions may be bulged outwardly from the opposite faces of the body sheet 2, they being in fact so bulged and retained in this position by blocks 5 of rubber felt, or any other suitable cushioning material, the blocks being disposed transversely of the opposite faces of the body sheet 2 at a point midway between the ends of the same and the associated plies 3.

The numeral 6 indicates a band of felt, of a suitable thickness, which is applied to the body or core 1 and which extends completely about the said core in the direction of the length of the core. This ply or band constitutes a backing of cushioning material for the polishing medium of the device, which medium is indicated in general by the 80 numeral 7 and comprises a band 8 of lambs' skin which is applied about the cushioning ply or band 6 and extends completely around the same longitudinally thereof. In order to prevent relative displacement of the several plies or bands with relation to each other and to the core or body 1, stitches 9 are run through the skin of the lamb's skin band 8, through the cushioning band 6, and through the members 2 and 3 comprising 85 the body or core of the device. The securing means 9 is therefore of such a character as to not in any way interfere with inward yielding of the polishing medium 7 and not being of a metallic nature is not liable to 90 contact with and mar the leather being polished.

Preferably the lamb's skin band 8, cushioning band 6, and strips 3, are of uniform width and their edges are in substantial 100 registration. However, the body sheet 2 is preferably somewhat wider than the other component parts of the polisher so that its lateral longitudinal edges will project to a slight extent as illustrated in Figures 1 and 105 3 of the drawings and thus enable the user of the polisher to obtain a secure hold upon the same. At the same time the body sheet 2 while relatively rigid and positioned in the manner stated to permit of the device 110

being firmly grasped, is not so positioned as to render it liable to come in contact with the shoe being polished.

It will be understood, of course, that one side of the polisher may be employed in polishing black shoes, and the other side may be employed in polishing tan shoes, the side not in actual use constituting a soft pad-like surface permitting of the polisher being employed without discomfort or inconvenience. It will also be evident that the peculiar construction of the core or body 1, enhances the resiliency of the polishing medium 7 as this medium is supported with a desired degree of firmness and is yet resiliently yieldable.

Having thus described the invention, what is claimed as new is:

1. A shoe polisher comprising a substantially rigid body member, yieldable supporting members upon opposite faces thereof, a cushioning medium extending about the body

and over the said yieldable supporting members, and a band of friction polishing material extending about the said cushioning medium. 25

2. A shoe polisher comprising a substantially rigid body member, resilient members disposed against opposite faces of the said body member and extending transversely 30 thereof, facing plies of flexible material secured at opposite edge portions to the said body member and extending over the said resilient members and having their intermediate portions supported thereby, a cushioning medium overlying the said plies, and a band of friction polishing material extending entirely about the said body and cushioning medium. 35

In testimony whereof they affix their signatures. 40
